(57) **CLAIM**

The ornamental design for a lidded container, as shown and described.

DESCRIPTION

FIG. 1 is a top front perspective view of a first embodiment of a lidded container, showing my new design;

FIG. 2 is a bottom front perspective view of the lidded container of FIG. 1;

FIG. 3 is a front view of the lidded container of FIG. 1;

FIG. 4 is a rear view of the lidded container of FIG. 1;

FIG. 5 is a left side view of the lidded container of FIG. 1;

FIG. 6 is a right side view of the lidded container of FIG. 1;

FIG. 7 is a top view of the lidded container of FIG. 1;

FIG. 8 is a bottom view of the lidded container of FIG. 1;

FIG. 9 is a top front perspective view of a second embodiment of the lidded container;

FIG. 10 is a bottom front perspective view of the lidded container of FIG. 9;

FIG. 11 is a front view of the lidded container of FIG. 9;

FIG. 12 is a rear view of the lidded container of FIG. 9;

FIG. 13 is a left side view of the lidded container of FIG. 9;

FIG. 14 is a right side view of the lidded container of FIG. 9;

FIG. 15 is a top view of the lidded container of FIG. 9;

FIG. 16 is a bottom view of the lidded container of FIG. 9;

FIG. 17 is a top front perspective view of a third embodiment of the lidded container;

FIG. 18 is a bottom front perspective view of the lidded container of FIG. 17;

FIG. 19 is a front view of the lidded container of FIG. 17;

FIG. 20 is a rear view of the lidded container of FIG. 17;

FIG. 21 is a left view of the lidded container of FIG. 17;

(Continued)

FIG. 22 is a right view of the lidded container of FIG. 17; FIG. 23 is a top view of the lidded container of FIG. 17; and, FIG. 24 is a bottom view of the lidded container of FIG. 17. The broken lines show portions of the article that form no part of the claimed design.

1 Claim, 24 Drawing Sheets
